TUBULAR METAL CHAIR FRAME

Charles J. Janosek, Cleveland, Ohio, assignor to
The Cleveland Welding Company, Cleveland,
Ohio, a corporation of Ohio

Application November 26, 1949, Serial No. 129,645

1 Claim. (Cl. 155—54)

1

The present improvements relating, as indicated to chairs, have more particular regard to a currently popular type of chair largely used as porch furniture, of which the seat and back comprise complementary stamped-up metal sheets. These members are secured together at their meeting edges and then are supported in a frame or base, formed out of re-bent tubing so as to provide two U-shaped side members having their rear lower ends connected by a separate frame tying member.

The present invention has more particular regard to the form and construction of the frame for such a chair. In the past such a frame has been a single continuous metal tube shaped to support the seat and back members. While such a frame provides the essential elements necessary to support the seat and back members, it presents many important difficulties. In the past the shipment from the place of manufacture of such chairs has been made by packaging the seat member, back member and frame unjoined, and supplying the necessary bolts and nuts and directions for easy assembly at the place of delivery. The shipment of the frame as a single continuous metal tube presented a bulky and expensive packaging and shipping problem. Also, since the said chairs are used essentially as porch furniture, the same problem with regard to bulk was presented to the user who wishes to store such chairs for a period of the year when they are not in use.

My invention permits the chair frame to be constructed in three separate members, the two U-shaped tubular side members and a separate frame tying member. Such construction of the frame permits the packaging and shipping of the three separate individual members of the chair frame in a relatively compact unit at less expense and yet they may readily and easily be assembled at the point of desired use. Such construction of the chair frame presents the added advantage of being easily taken apart and stored in a relatively smaller space during those periods of the year when such chair is not in actual use.

To the accomplishment of the foregoing and related ends, said invention, then, consists of the means hereinafter fully described and particularly pointed out in the claims.

The annexed drawing and the following description set forth in detail certain structures embodying the invention, such disclosed means constituting, however, but one of various structural forms in which the principle of the invention may be used.

2

In the annexed drawing:

Fig. 1 is a front perspective view of a chair embodying my present improvements;

Fig. 2 is a top plan view of the base of a chair frame embodying my present improvements;

Fig. 3 is a front view of the base of one of the separate side tubular frame members alone;

Fig. 4 is a side view of Fig. 3;

Fig. 5 is a front view of the frame tying member;

Fig. 6 is a side view of Fig. 5;

Fig. 7 is a vertical section taken on the plane indicated by the line 7—7 of Fig. 2;

Fig. 8 is an alternative joint to that in Fig. 7;

Fig. 9 is a top plan view of an alternative base of a chair frame embodying my present improvements;

Fig. 10 is a top plan view of an alternative base of a chair frame embodying my present improvements; and

Fig. 11 is a top plan view of an alternative base of a chair frame embodying my present improvements.

As shown in Fig. 1, the stamped-up metal sheets forming the back 1 and the seat 2 of the chair are secured together at their meeting edges and then are attached at points 3 and points 4 to the two side tubular frame members 5. Each of the two side tubular frame members are bent into a U-shape extending from end 6 to the lower end 8 and while supporting the back and seat members, they also act as a resilient member providing the chair with a spring-like comfort. The lower ends 8 of each of the side tubular frame members 5 are joined and supported by the frame tying member 9.

The base of the supporting frame for my improved chair, as shown in Fig. 2, has the lower ends 8 of each of the side tubular frame members 5 shaped so that the ends 8 are bent at point 10, so that such ends 8 are at a 90° angle to the vertical plane of each side tubular frame member 5. A portion of each of the side tubular frame members 5, extending from the lower end 8 of such members, toward point 10 of such members, being pressed to provide one substantially flat side to the end portion as shown in Fig. 4. A hole 11 is provided through the entire tube in the lower end section where one side of the tubular frame member has been substantially flattened.

The frame tying member 9 as shown in Figs. 5 and 6 is a partially tubular semi-hemispherically shaped member each end of which is provided with a hole 12. Such frame tying mem-

ber at each end rests firmly upon one of the side tubular frame members 5 so that the holes 12 in such frame tying member fall directly above the holes 11 in each side tubular frame member, as shown in Fig. 7. A bolt 13 is inserted through the hole 11 of each side tubular frame member 5 and hole 12 of each frame tying member 9, and a washer 14 and nut 15 are securely fastened upon the extending bolt 13, thus giving the joints strength and stability.

As shown in Fig. 7, the reason for the flattened portion of each of the side tubular frame members is to provide sufficient room for the head of the bolt 13 so that the head of the bolt will not extend below the lower level of the side tubular frame members 5. This provides the chair with better stability and prevents the heads of the bolt from digging into any grass carpet or the like upon which the chair may be placed. The head of the bolt 13 may be inserted from the top, in which case the nut 15 should not extend below the lower level of the side tubular frame members 5.

In Fig. 8 all of the parts of the chair remain the same except for the type joint provided, which is an alternative joint to that in Fig. 7. In Fig. 8 the frame tying member 9, instead of having holes 12 at each end, has a bolt 16 welded thereto at point 17. Such bolt 16 then is inserted into the holes 11 of the side frame members 5 and a washer 18 and nut 19 are securely fastened thereon.

Fig. 9 shows an alternative base for a chair wherein the side frame members 5 are the same as heretofore shown but the frame tying member 20 is also a tubular member of such size and shape that each end of such frame tying member is inserted into the end 8 of the side frame member 5, holes being provided in both the side frame members 5 and the frame tying member 20 at point 21, a bolt is inserted therethrough and a washer and nut securely fastened thereon.

Fig. 10 shows an alternative base for a chair wherein the side frame members 5 are the same as heretofore shown except that the ends of such side frame members 5 are not flattened as shown in Fig. 4 and the outer sides at point 18 of the side frame members 5 are bumped-in and holes provided therein for a nut and bolt. The frame tying member 22 is a tubular member of such size and shape that at each end it is inserted into the side frame members 5. A long slender bolt 24 is inserted with the head 23 of such bolt resting on said bumped-in portion of the side frame member 5 and the bolt 24 extends through the frame tying member 22 and out the hole in the opposite side frame member 5 where a washer and nut 25 are securely fastened.

Fig. 11 is an alternative base for a chair wherein the side frame members 5 are the same as

heretofore shown except that the ends 26 of such members are not bent at point 10 as shown in Fig. 2. The U-shaped tubular frame tying member 27 is so bent at points 28, and the ends of such member are of a shape and size so that each end of such frame tying member is inserted into the ends 26 of the side frame members 5, holes being provided in both the side frame members 5 and the frame tying member 27 at point 28, a bolt is inserted therethrough and a washer and nut securely fastened thereon.

The rigidity and stability of the chair have not been diminished and my improvement permits a chair to be manufactured and shipped in a convenient and less expensive manner and permits the quick and easy assembling of the chair frame at the place of delivery of the chair. It further provides the owner of the chair with a much less bulky storage problem during the periods when the chair is not in use. It also enables the owner of the chair, by breaking it down into its less bulky parts, to transport such chair easily to summer cottages, beaches and the like. Thus, it generally increases the utility of the chair and removes many of the limitations of use imposed by the chair used heretofore.

My invention may be adapted to any material suitable for a tubular frame for a chair. It is expected that this will generally involve the use of metal tubing and more particularly steel tubing.

Other modes of applying the principle of my invention may be employed instead of the one explained, change being made as regards the structure herein disclosed, provided the means stated by the following claim or the equivalent of such stated means, be employed.

I therefore particularly point out and distinctly claim as my invention:

A tubular steel frame for a chair, comprising two vertical spaced separate U-shaped steel tubular side members, the lower end of each such member bent to a 90° angle to the plane formed by such member and each such end being substantially flattened on its lower side, each such bent and partially flattened end being bolted to a steel partially tubular semi-hemispherically shaped frame tying member which joins the two said separate U-shape steel tubular side members.

CHARLES J. JANOSEK.
